UNITED STATES PATENT OFFICE.

WILLIAM H. GRAHAM, OF ST. LOUIS, MISSOURI.

DESIGN FOR A SINK-TRAP.

SPECIFICATION forming part of Design No. 21,528, dated May 10, 1892.

Application filed December 28, 1891. Serial No. 416,380. Term of patent 14 years.

To all whom it may concern:

Be it known that I, WILLIAM H. GRAHAM, of St. Louis, Missouri, have invented and produced a new and original Design for Traps, 5 of which the following is a specification, reference being had to the accompanying drawing, making part of this specification and showing the newly-designed trap in perspective.

10 The leading feature of the design consists in the general form of the body or main portion of the trap.

15 A represents said body or main portion. It is substantially a pear-shaped bulb, and an additional feature is its one-sidedness, the

lower portion of the bulb being inclined or set to the left, as viewed in the drawing. When viewed from the opposite side thereof, said inclination or set is to the right, of course. The complete design includes the right-angled tube B at the right-hand side of the bulb. 20

What I claim is—

The design for a sink-trap, as herein described and shown.

Witness my hand this 19th day of December, 1891. 25

WILLIAM H. GRAHAM.
